US00D818980S

(12) **United States Design Patent** (10) Patent No.: **US D818,980 S**
(45) Date of Patent: ** *May 29, 2018

(54) **ELECTRONIC DEVICE**

(71) Applicant: **Samsung Electronics Co., Ltd.**, Suwon-si (KR)

(72) Inventors: **Nam-Su Kim**, Seoul (KR); **Do-Hyung Ha**, Gwangmyeong-si (KR); **Sae-Hee Lee**, Incheon (KR); **Hyun-Sook Kim**, Seoul (KR)

(73) Assignee: **Samsung Electronics Co., Ltd.**, Suwon-si (KR)

(*) Notice: This patent is subject to a terminal disclaimer.

(**) Term: **14 Years**

(21) Appl. No.: **29/504,020**

(22) Filed: **Oct. 1, 2014**

(51) LOC (11) Cl. **14-03**

(57) **CLAIM**

We claim the ornamental design for an electronic device, as shown and described.

DESCRIPTION

FIG. 1 is a front perspective view of an electronic device, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

1 Claim, 6 Drawing Sheets
